US00D892086S

(12) **United States Design Patent** (10) **Patent No.:** **US D892,086 S**
Bonahoom et al. (45) **Date of Patent:** **** Aug. 4, 2020**

(54) **WIRELESS EARPHONES**

(71) Applicant: **SAMSUNG ELECTRONICS CO., LTD.**, Suwon-si, Gyeonggi-do (KR)

(72) Inventors: **Rhys Bonahoom**, San Francisco, CA (US); **Sean Bornheimer**, San Francisco, CA (US); **SeoungHyun Son**, San Francisco, CA (US); **Rob Shook**, San Francisco, CA (US)

(73) Assignee: **SAMSUNG ELECTRONICS CO., LTD.**, Gyeonggi-Do (KR)

(**) Term: **15 Years**

(21) Appl. No.: **29/679,088**

(22) Filed: **Feb. 1, 2019**

(51) LOC (12) Cl. **14-01**

(52) U.S. Cl.

USPC **D14/223**

(57) **CLAIM**

We claim the ornamental design for a wireless earphones, as shown and described.

DESCRIPTION

FIG. 1 is a left-side perspective view of wireless earphones, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines in the figures depict portions of the wireless earphones that form no part of the claimed design.
